UNITED STATES PATENT OFFICE.

CARLETON RUHE, OF OLEAN, NEW YORK.

MACHINE FOR HANDLING HIDES OR LEATHER IN BULK.

1,210,700.

Specification of Letters Patent. Patented Jan. 2, 1917.

Application filed July 8, 1915, Serial No. 38,834. Renewed May 29, 1916. Serial No. 100,699.

To all whom it may concern:

Be it known that I, CARLETON RUHE, a citizen of the United States, residing at Olean, in the county of Cattaraugus and 5 State of New York, have invented certain new and useful Improvements in Machines for Handling Hides or Leather in Bulk, of which the following is a specification.

My invention relates to improvements in 10 apparatus adapted for use in connection with a tanning vat or vats, for handling the hides or leather, while not necessarily restricted to such use.

An important object of the invention is to 15 provide a machine of the above mentioned character, which is adapted to raise the hides or leather, in bulk, from within the vat, and transport the same, to a desired remote point from the vat, thus dispensing 20 with the individual handling of the hides.

A further object of the invention is to 25 provide a machine of the above mentioned character, so constructed that the entire weight of the pack of hides or leather being removed from the vat, will be directly carried thereby, dispensing with the necessity 30 of suspending apparatus from the upper portion of a building, which ordinarily encloses the vat.

35 A further object of the invention is to provide a machine of the above mentioned character, having its elements arranged in a highly compact and convenient manner.

40 A further object of the invention is to 35 provide a machine of the above mentioned character, which may be constructed in a standard size, and which is adjustable for use in connection with vats, tracks, and associated elements of different sizes.

45 Other objects and advantages of the invention will be apparent during the course of the following description.

In the accompanying drawings forming a part of this specification and in which like numerals are employed to designate like parts throughout the same, Figure 1 is a side elevation of apparatus embodying my invention, showing the same arranged above a vat, which is shown in section, Fig. 2 is a 50 detail section taken on line 2-2 of Fig. 3, Fig. 3^a is a detailed section through a pair of winding drums, Fig. 3 is a plan view of the apparatus, Fig. 4 is a horizontal sectional view taken on line 4-4 of Fig. 1, Fig. 5 is an end elevation of the apparatus, Fig. 55 6 is a vertical longitudinal sectional view

through a pivoted bracket or arm, and, Fig. 7 is a transverse sectional view taken on line 7-7 of Fig. 6.

In the drawings, wherein for the purpose 60 of illustration is shown a preferred embodiment of my invention, the numeral 10 designates a supporting structure or frame as a whole, embodying lower longitudinal horizontal beams 11, having vertical outer and 65 inner beams or posts 12 and 13, rigidly attached thereto, as shown. These vertical posts 12 and 13 are preferably connected by diagonal braces 14, as shown.

The numeral 15 designates upper horizontal 70 longitudinal beams, rigidly secured to the top of the inner vertical posts 13 and the upper portions of the outer posts 12, as shown. The horizontal beams 15 are connected with the upper ends of the posts 12 75 by diagonal braces 16, as shown. The outer vertical posts 12 are rigidly connected by transverse horizontal beams 17.

The supporting structure or frame is 80 preferably formed of wood, while any other suitable material may be employed.

Secured to the outer edge of each post 12 by bolts 19 or the like are knuckles 18. These knuckles enter openings 20, formed in a horizontally swinging arm or bracket 21, as 85 clearly shown in Figs. 6 and 7. Bearing balls 22 are preferably arranged within the openings 20, as shown. The vertical portion of the bracket is preferably cylindrical and is provided with a vertical opening or openings 23, for registration with openings 24 formed in the knuckles 18, for receiving a pivot element or pin 25, as shown. The bracket 21 is provided in its lower end with a large opening 26, receiving the end of the 90 horizontal beam 11. The lower portion 27 of the bracket has an opening or recess 28, receiving the lower end of the pin 25. The bracket 21 embodies an outwardly extending horizontal arm 29, provided with a vertical 100 opening 30, receiving the shank or spindle 31 of a pivoted wheel carrier or frame 32. Roller bearings 33 are interposed between the frame 32 and the arm 29, as shown. The frame 32 embodies outer depending ears or 105 knuckles 34 and an inner ear or knuckle 35, for receiving flanged wheels 36. A stub-shaft or axle 37 passes through the apertures in the knuckles 34 and 35 and carries the wheels 36, with bearing rollers 38 interposed between the hubs of these flanged 110 wheels and the axle 37. The flanged wheels

36 are adapted to travel upon track rails 39. It is thus apparent that the brackets 21 are adapted to be swung horizontally with relation to the posts 12, and that the wheel frames 32 may be swung horizontally with relation to the brackets. By this means the wheels 36 may be swung inwardly or outwardly and remain parallel with relation to each other, to properly travel upon the track rails 39 of tracks of different gages.

To aid in the adjustment of the flanged wheels 36 as above stated, a jack, designated as a whole by the numeral 40, is rigidly secured to each of the beams 11, preferably upon its outer side and equidistantly spaced from the ends thereof, to elevate the side of the machine. This jack embodies a tubular body portion or standard 41, rigidly attached to the beam 11, and having a screw-threaded axial opening for receiving a screw 42, extending downwardly below the tubular standard 41, and having swiveled connection with a head 43, adapted to contact with a portion of the track or other support. It is apparent that the screw 42 may be rotated by any suitable means, such as by engaging its head 42' by a suitable wrench or tool.

As clearly shown in Fig. 3, the numeral 44 designates inner horizontal beams, rigidly attached to the beams 15 by any suitable means. Secured to the beams 44 and arranged upon opposite sides thereof are curved pairs of tracks 45 preferably formed of L-irons, also secured to the beams 15. There are four pairs of these curved tracks arranged within the four corners of the supporting structure, as shown. Slidably contacting with these curved tracks are four horizontally swinging arms 46, the outer ends of which are pivotally connected with the beams 15. As more clearly shown in Fig. 2, each arm 46 has a tubular pivot 47, pivotally mounted in an opening 47', in the beam 15. It is thus apparent that the inner free ends of the adjusting arms 46 may be swung inwardly and outwardly with respect to the supporting structure. Each adjustable arm 46 is provided near its outer end with an opening 48, near and above which is disposed a preferably grooved pulley 49. This pulley is carried by a shaft 49' journaled in bearings 50'. The arm 46 is also provided adjacent its tubular pivot 47 with bearings 51' receiving a stub-shaft 52', carrying a grooved pulley 51.

Passed about the pulleys 49 and 51 are flexible nonextensible elements, such as chains 52 or the like. There are four of these chains which are adapted to extend downwardly into a vat 53, for suitable connection with a tray 54, of any well known or preferred construction. At its corners this tray is provided with eye bolts 55, to which the chains 52 are attached.

Secured to each set of inner posts 13 are pairs of side beams 56, between which are rotatably mounted drums 57, carried by shafts 58. These shafts are rotated by gears 59 and 60. The gear 59 is rotated by a gear 61, which engages a gear 62, rotating the gear 60. The gear 61 is rotated by a sprocket wheel 62' driven by a sprocket chain 63. This sprocket chain extends upwardly to engage a sprocket wheel 64, rigidly mounted upon the end of a transverse rotatable driving shaft 65, journaled through bearings 66. The shaft 65 carries a gear 67, driven by a gear 68, which is rotated by a motor 69 or the like.

As more clearly shown in Fig. 5, the supporting frame or structure 10 has a large central opening entirely open at the bottom whereby the tray 54 and the pack of hides or leather may be moved upwardly into this opening. The winding mechanisms are disposed entirely out of this opening, being arranged upon or within the longitudinal sides of the machine. The motor 69 is also arranged exteriorly of the opening as it is disposed upon the top of the supporting frame. It is thus apparent that the elements of the machine are arranged in a highly compact and convenient manner.

In the use of the machine, the supporting structure or frame has its wheels 36 placed upon the track rails 39, to travel thereon. These track rails extend to or across the vat 53 and portions of the rails adjacent the vat are preferably constructed of wood. When the supporting frame is arranged directly over the vat, the tray 54 having the pack of hides or leather thereon is lowered into the vat, by suitable operation of the motor 69 and associated elements. When it is desired to remove the pack of hides or leather upon the vat, the motor is driven to elevate the tray, and this tray while in the elevated position moves with the supporting frame, along the track, to a desired remote position, thus transporting the hides or leather, in bulk, without individually handling the hides.

It is to be understood that the form of my invention herewith shown and described is to be taken as a preferred example of the same, and that various changes in the shape, size, and arrangement of parts may be resorted to without departing from the spirit of the invention or the scope of the subjoined claims.

Having thus described the invention, I claim:

1. In a machine for handling hides or leather in a pack or bulk, a traveling supporting frame having a main opening, a hide or leather support adapted to be moved into the main opening, pairs of substantially horizontally swinging arms carried by the upper portion of the supporting frame, pul-

leys carried by the inner free ends of the arms, a second set of pulleys carried by the outer ends of the arms, flexible elements attached to the support and passed about the 5 pulleys, and winding mechanism carried by the supporting frame and having the flexible elements connected therewith.

2. In a machine for handling hides or leather in a pack or bulk, a traveling frame, 10 a hide or leather support, pairs of substantially horizontally swinging arms having their outer ends pivotally connected with the sides of the frame, a set of pulleys carried by the free inner ends of the arms, a 15 second set of pulleys carried by the outer pivoted ends of the arms, flexible elements attached to the support and passed about the pulleys, and winding mechanisms mounted upon the sides of the frame and connected 20 with the flexible elements.

3. In a machine for handling hides or leather in a pack or bulk, a traveling supporting frame embodying side-members and having a main opening extending through 25 its bottom, a hide or leather support adapted to be moved into the main opening, pairs of substantially horizontally swinging arms having their outer ends pivotally connected with the side-members of the supporting 30 frame, a set of pulleys carried by the inner free ends of the arms, a second set of pulleys carried by the outer pivoted ends of the arms, flexible elements attached to the support and passed about the pulleys, winding 35 mechanisms mounted upon the side-members of the supporting frame, a transverse driving shaft mounted upon the upper portion of the supporting frame, driving connecting means between the shaft and the 40 winding mechanisms, and a motor mounted upon the supporting frame to drive the shaft.

4. In a machine of the character described, a wheeled frame having an opening extending 45 through its bottom, tracks connected with the frame near its corners and extending inwardly toward the center of the frame, supports movably mounted upon the tracks, pulleys carried by the supports, flexible elements 50 engaging the pulleys and extending downwardly below the same, a hide or leather support secured to the flexible elements to be moved thereby, and winding mechanism mounted upon the frame and 55 connected with the flexible elements to move them.

5. In a machine for handling hides or

leather in a pack or bulk, a traveling frame having an opening extending through its bottom, tracks connected with the frame 60 near its corners and extending inwardly toward its center, supports movably mounted upon the tracks, a set of pulleys carried by the supports, a second set of pulleys arranged adjacent the sides of the frame and 65 supported thereby, flexible elements engaging the sets of pulleys and extending downwardly below the first named set, a hide or leather support secured to the ends of the flexible elements, winding mechanisms arranged upon the sides of the frame and connected with corresponding ends of the flexible elements, and means to drive the winding mechanisms.

6. In a machine for handling hides or 75 leather in a pack or bulk, a traveling frame, pairs of substantially horizontally swinging arms having their outer ends pivotally connected with the sides of the frame, a set of pulleys carried by the inner free ends of 80 the arms, a second set of pulleys arranged near the pivoted ends of the arms, flexible elements engaging said pulleys, a hide or leather support connected with the flexible elements, winding mechanisms mounted 85 upon the sides of the frame and having connection with the flexible elements, and means to drive the winding mechanisms.

7. In a machine for handling hides or 90 leather in a pack or bulk, a traveling frame having a main opening extending through its bottom, tracks connected with the frame near its corners and extending inwardly toward its center, supports movably mounted upon the tracks, an inner set of pulleys 95 carried by the supports, an outer set of pulleys disposed adjacent the sides of the frame, winding mechanisms arranged within the sides of the frame below its top, flexible elements engaging the pulleys and connected 100 with the winding mechanisms, a motor mounted upon the top of the frame, a transverse driving shaft driven by the motor and connected with the frame, gearing connecting the ends of the transverse shaft and 105 winding mechanisms, and a hide or leather support connected with the flexible elements.

In testimony whereof I affix my signature in presence of two witnesses.

CARLETON RUHE.

Witnesses:
